US0D1017830S

(12) **United States Design Patent** (10) Patent No.: **US D1,017,830 S**
(45) Date of Patent: ** Mar. 12, 2024

(54) **MICRO-COLUMN GEL CARD**

(71) Applicant: **Aikang MedTech Co., Ltd**, Shenzhen (CN)

(72) Inventors: **Chuanguo Zhang**, Guangdong (CN); **Pengfei Lai**, Guangdong (CN); **Kai Zheng**, Guangdong (CN); **Shizhen Zhou**, Guangdong (CN); **Wuming Zhong**, Guangdong (CN)

(73) Assignee: **Aikang MedTech Co., Ltd**, Shenzhen (CN)

(**) Term: **15 Years**

(21) Appl. No.: **35/516,068**

(22) Filed: **Jan. 9, 2023**

(80) **Hague Agreement Data**

Int. Filing Date: **Jan. 9, 2023**

Int. Reg. No.: **DM/226217**

Int. Reg. Date: **Jan. 9, 2023**

Int. Reg. Pub. Date: **Jan. 27, 2023**

(30) **Foreign Application Priority Data**

Jul. 11, 2022 (CN) 202230437855.6
